NATHAN OTTINGER, OF NEW YORK, N. Y.

CORRESPONDENCE DEVICE.

1,412,668.

Specification of Letters Patent. Patented Apr. 11, 1922.

Application filed April 27, 1917. Serial No. 164,967.

To all whom it may concern:

Be it known that I, NATHAN OTTINGER, a citizen of the United States of America, and a resident of the borough of Manhattan, in the city, county, and State of New York, have invented certain new and useful Improvements in Correspondence Devices, of which the following is a specification.

The present invention relates to improvements in correspondence devices and particularly such devices as disclosed in my co-pending application, Serial No. 54115, filed October 5, 1915.

Generally stated, the purposes of the invention embodied in this application include among others the following objects, viz:

To provide a means whereby part of a free edge of the retaining member referred to in such co-pending application may, while actually open, be given a closed appearance and be so made as to prevent any foreign matter coming underneath the retaining member when the device is closed and ready for mailing; to provide means by which, when the device is received in a sealed condition, it may be opened easily without any opening machine, without tearing the contents and leaving a substantially straight and clean edge for filing purposes; and to provide means whereby the device may be used for correspondence or similar purposes in a form which, while unsealed and open to inspection by the Post Office Department is yet held closed sufficiently to prevent the mutilation or dropping out of the contents, and thus securing all the advantage of a letter paying the rate of postage of first class matter, while coming within the requirements of the one cent postage rate. A still further object is to provide such a device which may, though it need not be, be manufactured from a single sheet of paper or other suitable material, and which will be simple in construction and inexpensive to manufacture.

With these and other objects in view, embodiments of my invention are shown in the accompanying drawings, and will be hereinafter more fully described with reference thereto, and finally pointed out in the claims.

In the accompanying drawings,

Figure 1 is a plan view of one form of my improved invention, showing the blank before folding or sealing;

Figure 2 shows the same ready to be written upon;

Figure 3 shows the same folded, sealed and addressed;

Figure 4 is a plan view of a modified form of the construction for a form of the device which will be securely closed though unsealed;

Figure 5 shows the same form folded up closed and unsealed ready for mailing;

Figure 6 is a plan view of another form of the device intended to be mailed as a closed but unsealed correspondence device;

Figure 7 shows the same folded closed but unsealed and ready for mailing;

Figure 8 shows a further modified form; and

Figure 9 shows a still further modification.

Similar reference characters indicate corresponding parts throughout the several figures of the drawings.

Referring to the drawings, and more particularly to Figure 1 thereof, a portion 10 of a sheet is provided with a flap 15 having an extension 15^a and also with flaps 13 and 17 and with cuts 17^b and 17^c. The outer edge 28 of the flap 15 is bent over along the line 23 so that when the flap 15 is folded down as hereinafter stated the said bend will be in the direction of the portion 10. The portion 11 is provided with a flap 19 intended to be secured upon its underside to the underside of the portion 11 by gumming or other securing means as far as the line 20, leaving the space between said line and the outer edge 24 of said flap unsecured and forming a species of pocket. The portions 10, 11 and 12 and the flap 15 are provided with a perforated line 18 so located that when the flap 17 is folded upon the portion 10 the said line of perforations will be between said flap and the line 22^a along which the flap 13 is folded as hereinafter stated. The portion 12 is provided with a transverse perforated line 30 and also with an extended portion 29 which is provided with what is substantially a duplication, for purposes of return correspondence, of the structure which will be formed in the manner presently stated upon the portion 10.

In forming the improved correspondence means from the blank just described, the extended flap 15^a is folded under the flap 110

15 which is then folded down upon the portion 10 and the flap 13 is folded over the flap 15 along the line 22^a and secured thereto at the contacting points, one method of 5 securing same being by gumming the flap 13 and a part of the portion 10 as for instance up to the line 14. The point 16 of the flap 15 will then be on a line with the edge 25 enabling the folds 11 and 12 when 10 folded along lines of folding 22 and 26 which may be prepared folds, to be easily inserted within the retaining member preferably by a rotary motion around the point 27 or in proximity thereto. The flap 17 is 15 gummed or otherwise secured to the portion 10 along the line 17^a, preferably not above the cut 17^b thus forming a spring flap. If it is desired to seal the device the remaining portion of the flap 17 may be gummed 20 but preferably not above the line of the cut 17^b. The flap 19 is then folded backward upon the portion 11 along the line 19^a and the undersides of the said portion 11 and the flap 19 are then secured together except that the said flap 19 remains unsecured 25 in the space between line 20 and the outer edge 24 of said flap, thus forming a pocket which, when the device is folded up along the line of folding 22 will engage the edge 30 28 of the flap 15 and hold it closed. It is obvious that the flap 15 may be given a circular, semi-circular, rectangular, irregular or any other shape and that the flap 19 may be correspondingly shaped so that the 35 aforesaid pocket will properly engage with the flap 15. Examples of such other shapes are given in Figures 4, 5, 6 and 7. The cuts 17^b and 17^c of the portion 10 are provided to enable the spring flap to be bent 40 easily backwards or forwards. The bend in the flap 15 along the line 23 may be accomplished either by physically bending the paper or by applying some chemical or other substance which will produce that result. 45 It is obvious that the flap 19 may be formed from a separate piece of material secured to the underside of the portion 11 to perform the same functions and also that any of the flaps 13, 15 or 17 may likewise 50 be made from a separate piece of material. In the form illustrated in Figure 2, the device may be readily placed in a typewriting machine, printing press or the like or may be written upon by hand, the entire 55 name, address and letter being written at one operation, the name and address upon portion 15 and the body of the letter on the portions 10, 11 and 12.

When the letter is completed the device 60 is folded along the lines of folding 31, 26 and 22 and the portions 11 and 12 should then be placed within the pocket formed by the portions 10 and 15, the pocket formed between the lines 20 and 24 engaging the 65 bent edge of the portion 15 between the

lines 23 and 28 and extension 15^a will then be underneath the portion 11 and 12; the spring flap 17 is then bent backwards by means of the cuts 17^b and 17^c along the line 17^a and the portion 17^d of said flap is then 70 placed underneath the portion 15 and over the portion 12 thus forming with the extension 15^a an interlocking means, and the rest of the flap 17 will enclose the portions 11 and 12. In this way, a device is obtained which while easily open to postal inspection required by the lower postage rates will yet form a securely held and closed packet or correspondence device. If it is desired to seal the same the entire flap 17 80 but preferably not above the cut 17^b may be gummed and sealed.

Figure 3 shows the device folded up and ready for mailing.

When the device is received it is opened, if 85 not in sealed form, by merely pressing back the spring flap 17 and a single pull will then open out the entire device and any contents that may have been placed therein. If the letter has been sealed, it may be opened by 90 tearing along the perforated line 18, thus removing entirely the spring flap 17 and the extension 15^a and leaving a straight edge upon the device which with its contents, may be fully opened with a single pull. 95

If it be desired to use the return device formed upon the portion 12 and the extended portion thereof it is only necessary to tear off such return device along the perforated line 30 and then to fold it up in substantially the 100 same manner above set forth.

It is obvious that that part of the portion 12 which is below the perforated line 30 may, if desired, instead of being employed for a return device contain a check, receipt or any 105 similar paper which it is desired to detach from the body of the device.

Figure 4 is a blank of another form intended to be used without sealing. In this form the flap 15 is to the left of the portion 110 10 and is provided with a flap 35. The flap 15 is bent over upon the portion 10 along the line 22^a and the flap 35 is bent over upon the underside of the portion 10 along the line 33 and secured to such underside by gumming or other means. The flap 15 in this 115 form is given a circular or semi-circular shape. The portion 11 is provided along its right hand edge with a spring flap 17 which is secured along the line 17^a, and a cut 17^b is 120 provided along a line of folding 22, and another cut is provided in the portion 11 along the line 32. This last mentioned cut begins at a point equally distant from the line 22 with a point upon the flap 15 after it is folded 125 over, in line with the line of said cut 32. Portion 11 is provided with another cut 34 which is so arranged that when the folds 11 and 12 are folded into the retaining member formed by the flap 15 and the portion 10, the said 130

cut will engage upon and hold down the flap 15 along its edge 28.

When the communication has been written upon the device, such device is folded up 5 along the lines of folding 22 and 26 and the portions 11 and 12 are then inserted beneath the retaining member preferably by a rotary motion around or near the point 27 whereupon the cut 34 will automatically engage 10 over a portion of the flap 15 as aforesaid and a portion of the spring flap between the point 32^a and 32^b will automatically engage over some of the right hand portion of the flap 15.

The spring flap 17 is then bent forward 15 and its free edge 17^c engages over the underside of the portion 10 effectually closing the device though unsealed.

Figure 5 shows the same device folded up and ready for mailing.

20 When the device is received, all that is necessary in order to open the same is to press the spring flap forward and pull out the entire device and contents with one pull.

Figure 6 is a blank of another modified 25 form of my invention intended for an unsealed device, in which the flap 15 is given a rectangular shape and the flap 13 is provided with extensions 13^a and 13^b, and the portion 11 and the flap 15 are cut away to the 30 points 13^d along the lines of folding 22 and 15^b. In this modified form the device is made by folding the extension 15^a underneath the flap 15 and then folding the flap 15 down upon the portion 10 and then folding 35 the flap 13 along the line 22^a upon the portion 10 and the flap 15 and pasting or otherwise securing the extensions 13^a and 13^b to the underside of the portion 10 along the portions 13^c of the lines of folding 15^b and 22.

40 After the communication is written the portions 11 and 12 are folded along the lines of folding 22 and 26 and are then folded into the retaining member and between flap 15 and the extension 15^a. The flap 17 is then 45 folded over the device along the lines 17^c and the portion 17^d of said flap is inserted underneath the flap 15, the flap 17 thus forming with the extension 15^a an interlocking means.

In Figure 8 I have shown a still further 50 modification, in which the flap 15 is formed integral with the upper edge of the portion 10, and is provided at its left hand edge with a flap 40 which is sealed to the back of the portion 10. The edge 41 of the flap 15 is 55 preferably parallel to the longitudinal edges of the fold 10, and at its left hand end is brought down to a point slightly above the extremity 27 of the transverse line of folding by an ogee curve as at 42, to facilitate folding 60 in of the portion 11. In Figure 9 the flap 15 of the form shown in Figure 4 is provided with a curved portion 42.

I have illustrated and described preferred 65 and satisfactory forms of my invention, but it is obvious that changes may be made there-

in within the spirit and scope thereof, as defined in the appended claims.

I claim:

1. In a device of the character described, a sheet of material foldable to form two or 70 more folds, one of said folds having a stationary retaining member permanently fastened thereto so as to form with such fold a permanent pocket of which said fold constitutes the underside, and the retaining 75 member the upper side, said retaining member being attached along one of its principal dimensions in proximity to a considerable portion of an edge of said fold, which edge is adjacent a line of folding, said retaining 80 member adapted to receive a considerable portion of that edge of another fold which corresponds to the edge of the first mentioned fold in proximity to which the said retaining member is attached, both of said 85 edges being adjacent said line of folding, said sheet of material being provided with a marginal sealing flap independent of said retaining member in a direction transverse to said line of folding and a weakened line 90 spaced from said sealing flap and extending over at least two folds in a direction transverse to said line of folding and located between the two edges of the first mentioned fold which are adjacent said line of folding. 95

2. In a device of the character described, a sheet of material foldable to form two or more folds, one of said folds having a stationary retaining member permanently fastened thereto so as to form with such fold 100 a permanent pocket of which said fold constitutes the underside, and the retaining member the upper side, said retaining member being attached along one of its principal dimensions in proximity to a considerable 105 portion of an edge of said fold, which edge is adjacent a line of folding, said retaining member adapted to receive a considerable portion of that edge of another fold which corresponds to the edge of the first mentioned fold in proximity to which the said retaining member is attached, both of said 110 edges being adjacent said line of folding, and a bent over marginal portion provided on said retaining member along a free edge 115 thereof, such bent over portion constituting a flap and being bent towards the first mentioned fold so that the body of said retaining member is out of contact with said fold and only the free edge of said member contacts with the fold. 120

3. In a device of the character described, a sheet of material foldable to form two or more folds, one of said folds having a stationary retaining member permanently fastened thereto so as to form with such fold a permanent pocket of which said fold constitutes the underside, and the retaining member the upper side, said retaining member being attached along one of its principal di- 125 130

5   dimensions in proximity to a considerable portion of an edge of said fold, which edge is adjacent a line of folding, said retaining member adapted to receive and enclose a
10   considerable portion of that edge of another fold which corresponds to the edge of the first mentioned fold in proximity to which the said retaining member is attached, both of said edges being adjacent said line of folding, means for enclosing the edge of
15   said other fold opposed to said enclosed edge, and means comprising a spring flap to hold closed a considerable portion of a free edge of such retaining member when the said device is folded up, so that all interior spaces of said device are substantially closed in the folded position of said device.

4. In a device of the character described, a sheet of material foldable to form two or
20   more folds, one of said folds having a stationary retaining member permanently fastened thereto so as to form with such fold a permanent pocket of which said fold constitutes the underside, and the retaining
25   member the upperside, said retaining member being attached along one of its principal dimensions in proximity to a considerable portion of an edge of said fold, which edge is adjacent a line of folding, said retaining

30   member being disposed in its entirety upon said fold and adapted to receive a considerable portion of that edge of another fold which corresponds to the edge of the first mentioned fold in proximity to which the said retaining member is attached, both of said edges being adjacent said line of folding, and a flap attached to said retaining member, said flap extending beyond the first mentioned fold in a direction transverse to said adjacent edge, and adapted to fold between said retaining member and first mentioned fold, and another flap independent of said retaining member and extending along that free edge of said first mentioned fold which is adjacent the said line of folding, 45 said other flap adapted to be inserted between the retaining member and the first mentioned flap and to form in conjunction therewith a means for locking the device closed. 50

In testimony, that I claim the foregoing as my invention, I have signed my name in presence of two subscribing witnesses.

NATHAN OTTINGER.
